UNITED STATES PATENT OFFICE.

CHARLES GILLINGS, OF LIVERPOOL, ENGLAND, ASSIGNOR, BY MESNE ASSIGNMENTS, TO AUTOMATIC ELECTRIC INC., OF CHICAGO, ILLINOIS, A CORPORATION OF DELAWARE.

TELEPHONE SYSTEM.

Application filed June 30, 1924, Serial No. 723,124, and in Great Britain July 12, 1923. Renewed February 14, 1929.

The present invention concerns improvements in or relating to telephone systems and more particularly to those systems in which calls are set up from a manual subscriber over 5 numerical switches controlled by an operator.

In the Patent No. 1,651,401 to Mercer and Tench, an arrangement is described in which a number of operators in a mechanical tandem exchange have access to a group of 10 impulse senders in common whereby a considerable economy is obtained over the arrangement in which a number of impulse senders are provided individual to each operator.

It has been found, more particularly in 15 large networks, that it is desirable to have means for translating the whole or a portion of a number set up by the operator so that impulses may be sent out which do not correspond with the number set up.

The present invention provides an impulse 20 sender adapted to bring about this result in an arrangement on the general lines disclosed in the application above referred to.

According to one feature of the invention 25 an impulse sender is provided in which a set of keys adapted to be operated in accordance with the exchange and the number of a wanted party is arranged to control the transmission of impulses through the intermediary of a translating device to route the call to the desired exchange and independently of the translating device to operate switches in said exchange and establish connection with the 30 wanted party.

According to another feature of the invention 35 a set of digit keys adapted to be operated in accordance with the exchange of a wanted party, is arranged to control through the intermediary of a translating device the transmission of series of impulses which may differ in number and value from the number set up on the digit keys to route the call to the desired exchange.

A further feature of the invention is the 40 use of an impulse sender in which certain sets of a plurality of sets of storage relays corresponding in number to the number of digits in the designation of a subscriber, are adapted to control the transmission of impulses 45 through the intermediary of a translating device.

Still another feature of the invention is the provision of an impulse sender controlled by a set of keys under the control of an operator, in which predetermined series of impulses having no numerical relationship to the number set up, are adapted to be transmitted automatically to route the call to an operator's position when the impulse sender 55 is set for a number which does not correspond to a subscriber's number.

These and other features not specifically mentioned at this point will be more fully understood from the following description 60 of a preferred form of the invention, though it will be understood that this is given by way of example only, and that various modifications could be made in the circuit details without exceeding the scope of the invention. 65

Referring now to the accompanying drawings, Fig. 1 shows schematically the general layout of the system while Figs. 2 to 8 show by means of detailed circuit diagrams the 70 actual apparatus used by an operator in the mechanical tandem exchange in setting up a connection from a subscriber of a manual exchange to an automatic subscriber in a third exchange.

Considering first Fig. 1, the operations involved in setting up a call will be briefly traced through. When the manual subscriber A removes his receiver, he attracts the attention of the operator at his exchange in the usual manner and she thereupon inserts 75 the answering plug P^1 of the cord O into his jack J^1 . Upon learning his requirements, she will communicate with the operator at the mechanical tandem exchange over an order wire (not shown) and inform her of 80 the number of the wanted party. She will then be assigned a free junction line, for instance the line L^2 , and will thereupon insert the plug P^2 into the jack J^2 . The B operator at the tandem exchange, at the 85 same time as she notifies the A operator of the junction line to be used, will press the assignment key associated with this line, whereupon the sender selector SS^1 associated with the outlet with which the wipers 90 of the outlet finder OF are then in engagement will be started up and commence hunting to find an idle set of impulse sending equipment. When this is found it will be as- 95

sociated with the key set K, and the B operator will be notified by the lighting of a lamp. She will then set up the number on the key set and in accordance with the first digit, 5 the first storage relay group SR¹ will be influenced over the outlet finder OF in the position shown, back contact and armature T¹, sender selector SS¹, armature W¹ and its back contact, transfer switch TS in first position to first storage relay group SR¹.

Upon the release of each key the transfer switch will be moved on one step so that each digit of the required number will be stored on the appropriate set of storage relays SR¹, 15 SR², SR³, SR⁴ . . . SR⁷.

When the B operator presses her start key (assuming that the plug P² has already been inserted in the jack J²), the armatures T¹ and W¹ will be operated and the code switch 20 CS will be started up and will proceed to hunt until it finds terminals which have been marked by the operation of the storage relay groups SR¹, SR² and SR³, whereupon the shunt field relay SF is operated and stops the 25 switch CS.

The first three contacts of the sender control switch SCS are then controlled over another set of wipers of the switch CS so as to effect the sending of trains of impulses which 30 will in general differ in value and possibly also in number from these corresponding to the number recorded on the relays of the first three storage relay groups. The circuit for the transmission of impulses extends from 35 the impulse sender IS over front contact and armature W¹, sender selector SS¹, armature T¹ and its front contact to the connecting point C¹ and thence over the line L² to the selector E. Further impulses then operate 40 selectors such as F and succeeding selectors and a connector. The sender control switch SCS is moved on one step after the termination of each series of impulses and after the first three series have been sent engages its fourth 45 bank contact. Bank contacts 4, 5, 6 of the switch SCS are connected to the code relays CR which are only used in case it is desired to send more than three exchange digits. If, as will usually be the case, only three exchange 50 digits are being sent, the switch SCS will be moved quickly through positions 4, 5 and 6 to position 7, in which position the impulse sender is controlled by the storage relay group SR⁴ to send the first numerical 55 digit. The remaining numerical digits are then sent in the usual manner under the control of storage relay groups SR⁵, SR⁶ and SR⁷. In this case the transfer switch TS is not released when the transmission of 60 pulses commences but remains in operated position throughout the sending of impulses, and is released with the remainder of the apparatus when this is finished.

The outlet finder OF is moved on one step 65 each time the start key is operated so that the

operator may commence setting up another connection as soon as she has finished with the previous one.

The selector E may have access to a selector F in common with a line coming from an automatic subscriber whose connections will be set up over the individual line switch C with the aid of the director or register translator D. When the connection has been fully set up 70 the contact B is closed and the director cut 75 out.

Referring now more particularly to Figs. 2-8 the operations involved in the sending of a call will be traced through in detail. The A operator in the originating manual exchange, 80

after ascertaining the calling subscriber's wishes will communicate with the B operator at the mechanical tandem exchange over an order wire which is not shown. The B operator will thereupon assign to the A operator an idle junction line, for instance, that comprising conductors 302 and 303. At the same time she will press the corresponding assignment key 304 whereupon the assignment relay 305

is energized and operates its contacts 306, 307, 308, 309 and 310. At armatures 306-309, inclusive, circuits are prepared for the trunk connecting relays 312, 313, 314 and 315. It

will be assumed for the purpose of description that the first outlet in the one which is to be used and consequently the only armature which will perform any useful function in this case is armature 306 which prepares a circuit for relay 312. At armature 310, earth is connected by way of a chain of contacts such as armature 311 on all the assignment relays to lead 400 which extends to equipment individual to the position and common to all the outlets.

The effect of this earth connection is to energize the relays 408, 409, 410 and 420, the circuits for the two latter extending from earth on lead 400, winding of relay 410, wiper 460 and the contact with which it is in engagement, normally closed spring 462 of the sender disconnect key, armature 434 and its back contact, relay 420 to battery. Relay 408 operates its armatures 452 and 453 thereby closing contacts for a purpose which will be fully described hereafter. Relays 409 and 410 at contacts 465 and 466 control a circuit for the driving magnet 467. As, however, relay 409 is slightly slow to pull up, contact 466 will always be opened before contact 465 closes and a circuit will in the normal course of operation never be completed for magnet 467, even should earth be connected to lead 469 which will not in general be the case. Relay 420 upon energizing, at armature 432 completes a circuit for cut off relay 419 and driving magnet 445 in series which circuit may be traced as follows: earth, resting contact and armature 492, armature 456 and its resting contact, wiper 455 and the contact with which it is in engagement, armature 452

and its working contact, armature 432 and its working contact, winding of relay 419, interrupter contact 446, driving magnet 445 to battery. Relay 420 also at armature 433 connects the test wiper 474 of the sender selector by way of resting contact and armature 451 and armature 431 and its resting contact to the junction of relay 419 and driving magnet 445 in the above circuit. Consequently 5 if there is an earth on the contact with which wiper 474 is in engagement, relay 419 will be short circuited, and the switch will commence to hunt in the usual manner until wiper 474 engages with a contact which is not earthed. 10 15 When this occurs, relay 419 will energize in series with driving magnet 445, which latter however, does not now receive enough current to energize it. Relay 419 upon operating, at armature 430 completes a locking circuit for itself to the earth on back contact of armature 444, at armature 431 disconnects the driving magnet 445 and places earth on test wiper 474 and at armature 429 completes a 20 circuit for relay 418. Relay 418, upon operating, at armatures 424, 425 and 426 connects the wipers 456, 457 and 458 through to the wipers 470, 471, 472 respectively, wiper 459 having previously been connected through to wiper 473 at armature 428 by the operation 25 of relay 419. At armatures 475 and 427, battery and earth respectively are connected to leads 402 and 403 extending to the trunk circuit, the earth connection to lead 403 being over the normally closed spring 464 of the 30 sender disconnect key. A branch circuit from this spring also extends to the sender guard lamp 476 which therefore lights and indicates that the corresponding outlet is in use. The connection of earth to test wiper 35 40 474, in addition to making the impulse sender busy to other sender selectors, has the effect of energizing relay 525. This relay thereupon operates at armature 526 opens a point in the circuit of release magnet 508 so that this will not operate when the off-normal contacts 509 close, at armatures 527 and 528 45 opens points in the circuit of release relay 521 and at armature 530 closes a point in the chain busying circuit the nature and code 50 of operation of which will be fully described subsequently.

The effect of the connection of battery and earth to the leads 402 and 403 is to complete an energizing circuit for the trunk connecting relay 312 which circuit may be traced from the battery connection on lead 402 by way of the normally closed contacts controlled by armature 320, winding of relay 312 and armature 306 and its working contact to earth on lead 403. Relay 312 therefore operates, at its armatures 316 and 317 connects the outgoing trunk conductors 336 and 337 to the impulsive leads 405 and 407, and at armature 318 completes a circuit from the normal battery connection on lead 406 by way of resting

contact and armature 439 to the assignment lamp 322, armature 332 and its resting contact and flashing interrupter 333 so that the assignment lamp 322 commences to flash. Relay 312 also at armature 319 prepares an 70 energizing circuit for relay 338, at armature 320 opens its initial energizing circuit and completes a locking circuit for itself by way of the normally closed spring 326 of the busy or cancel key and at armature 321 shunts armature 306 so that its own circuit is not interrupted when relay 305 deenergizes upon the release of the assignment key 304. The operator keeps the assignment key pressed until the lamp 322 lights, whereupon she knows 80 that the outlet finder and sender selector switches are functioning correctly and that her key set is now connected to an idle set of impulse sending equipment.

The apparatus is now in readiness for registering the wanted number as set up upon the key set. Suppose that the numerical equivalent of the wanted number is 8765432.

When the key 8 is pressed a circuit is completed from earth, operated spring of digit 90 key 8, lead 480, wiper 457 and the contact with which it is in engagement, front contact and armature 425, back contact and armature 440, wiper 471, lead 501, armature 534 and its back contact, wiper 539 of the transfer switch 95 in first position, lead 556, lower winding of relay 560, lead 563, back contact and armature 519, winding of relay 514 to battery. Relays 514 and 560 energize in this circuit and the former at armature 515 completes a circuit for relay 510, at armature 516 opens a point in the circuit of the stepping magnet 507, and at armatures 517 opens a point in the circuit of relay 531 which is made slightly slow to pull up. Relay 510 upon operating, at 105 armature 511 removes earth from the eighth contact in the bank of wiper 538, which operation serves no particular purpose at the present time at armature 512 prepares a circuit for the stepping magnet 507 and at armature 110 513 opens another point in the circuit of relay 531. Relay 560 upon operating, at armature 564 completes a locking circuit for itself through its upper winding to lead 552 and thence over back contact and armature 523 115 and lead 504 to earth at armature 427. Relay 560 also operates its armatures 568 and 570 but this is without any immediate effect.

A similar circuit is also completed from the other operated spring of digit key 8 over 120 lead 481, wiper 458 and the contact with which it is in engagement, front contact and armature 426, back contact and armature 441, wiper 472, lead 502, armature 535 and its back contact, wiper 540 of the transfer switch 125 in first position, lead 557, lower winding of relay 561 to lead 553 and thence to battery through the winding of relay 514 as before. The effect of the current flowing through relay 514 is the same as previously described, 130

while relay 561 operates and locks itself up to lead 552 as did relay 560.

When the operator releases the key 8, the circuit through the lower windings of relays 560 and 561 and relay 514 is opened and relay 514 accordingly deenergizes, thereby opening the circuit of relay 510. Relay 510 is made slightly slow to release by being provided with a short circuited winding and consequently while it holds up a circuit is momentarily completed from earth, armature 516 and its back contact, front contact and armature 512, winding of stepping magnet 507 to battery. Stepping magnet 507 thereupon operates to advance the wipers of the transfer switch one step into engagement with the second set of bank contacts.

When the operator presses her digit key 7 for the next digit, a circuit is completed from earth, operated spring of digit key 7, winding of relay 482 to battery. Relay 482 upon energizing, at its armature 483 completes a circuit as follows: earth, front contact and armature 485, wiper 456 and the contact on which it is standing, working contact and armature 424, wiper 470, lead 500, armature 533 and its back contact, wiper 538 now in second position, through the lower winding of relay 571 to lead 553 and through the winding of relay 514 to battery as before described. The relays in all the storage groups are provided with two windings connected up as shown for the first storage group and the contacts are arranged similarly to those shown for the first storage group except that the initial connection over the armature such as 567 is different in each case.

A circuit is also completed by the operation of digit key 7 from earth, operated spring of key 7, lead 479, wiper 459 and the contact with which it is in engagement, 442, wiper 473, lead 503, armature 522 and its back contact, armature 536 and its back contact, wiper 541 in position 2, through the lower winding of relay 573 to lead 553 and thence to battery through the winding of relay 514. A branch of this circuit extends from back contact of armature 522 over back contact and armature 513, back contact and armature 517 through the winding of relay 531 to battery. Relay 531 however, as stated above, is slightly slow to pull up and consequently does not energize before its circuit is opened at armature 517 by the operation of relay 514. Relays 514 and 510 operate as before and jointly control the stepping on of the transfer switch when the digit key is released. Furthermore by the operation of the lower armatures of relays 571 and 573, battery is connected by way of armature 572 to lead 574 corresponding to the digit 7.

The operator will now press the key 6, whereupon circuits similar to those previously described may be traced over leads 502 and

503 for the relays 575 and 576 in the third storage group. These operate and lock up in the same manner as the other storage relays, relay 514 being energized in series with them, on its deenergization moving the transfer switch into fourth position. By the operation of relays 575 and 576 in the third storage group, earth is connected over armature 577 to lead 578 corresponding to the digit 6.

In a similar manner the operation of the digit keys for the remaining digits 5432 brings about the energization of the corresponding relays in the storage groups 4, 5, 6 and 7, the transfer switch being moved on one step each time a key is released.

After the full seven digits have been sent, however, the transfer switch is moved into the eighth position and upon the deenergization of relay 510 a circuit may be traced as follows: earth, armature 511 and its back contact, eighth contact in the bank of wiper 538 and said wiper, back contact and armature 533, lead 500, wiper 470, armature 424 and its front contact, contact in the bank of wiper 456 and said wiper, armature 485 and its back contact, winding of relay 486 to battery. Relay 486 is energized in this circuit and at its armature 488 completes a circuit for stepping magnet 467 so that the wipers of the outlet finder are advanced one step and at its armature 487 completes a circuit for start relay 489. The circuit of relay 486 is opened as soon as wiper 456 leaves the contact on which it was resting and the relay is then deenergized. The operation of relay 489 prepares four starting circuits only one of which however can be operative in any one case since only one call can be set up at a time. In the present instance, a circuit is now completed from earth, armature 427 and its front contact, front contact and armature 490, winding of relay 422 to battery. Relay 422 upon operating, at armature 438 completes a locking circuit for itself independently of armature 490, at armature 437 removes the battery connection from lead 402 so as to prevent any other truck relays associated with this outlet from energizing when another assignment key is pressed and at armature 436 prepares a circuit for relay 423.

It should be noted that with the arrangement described, if the operator sends the full seven digits, which is the maximum for which the arrangement is designed (though obviously comparatively slight alteration is necessary to enable a larger number to be dealt with), no special operation on her part is necessary in order to initiate the actual sending of impulses, since the relay 486 performs the same function as the start key 483. If, however, a less number of digits is being sent, all the required operations can be made to take place without any alteration to the apparatus, the only difference being that it

will now be necessary for the operator to press the start key when she has set up all the digits that are required.

For the sake of convenience of description it will be assumed that the pressing of the start key or equivalent automatic operation takes place before the A operator has plugged in and that the above described effects are produced. When the A operator plugs in, a supervisory circuit is completed over the lower talking conductor 303 and the normally closed springs 348 of the emergency order wire key for relay 339. Relay 339 upon operating, at its armature 340 completes a circuit for the polarizing winding of relay 342 and also a circuit for the relay 338 which latter circuit extends as follows: earth, armature 340 and its front contact, normally closed spring 325 of the busy or cancel key, front contact and armature 319, relay 338 to battery. Relay 338 upon operating, at its armature 334 and 335 closes points in the outgoing trunk leads, at its armature 327 completes a locking circuit for itself, at its armature 332 substitutes a direct earth connection for the earth connection by way of the flashing interrupter 333 and its armatures 328, 329, 330 and 331 prepares circuits for initiating the generation of impulses. In this case also, only one of these circuits can be usefully operative at a time. The joint operation of armature 332 and 341 completes a circuit for the trunk busy lamp 323 and the assignment lamp 322 so that the latter, which has previously been flashing under the control of the flashing interrupter 333, will now glow steadily.

In consequence of the operation of armature 328, a circuit is now completed which may be traced from earth, armature 427, and its front contact, normally closed spring 464 of the sender disconnect key, lead 403, front contact and armature 321, front contact and armature 328, lead 403, front contact and armature 321, front contact and armature 328, lead 404, armature 436 and its front contact, winding of relay 423 to battery. Relay 423 therefore energizes and upon operating, at its armatures 440, 441, 442 and 443 connects the wipers 471, 472, 473 and 474 to the leads 407, 405, 404 and 403 respectively. Furthermore at armature 439 it removes the battery connection from lead 406 so that assignment lamp 332 is extinguished and at armature 444 opens the circuit for relay 419. Relay 419 slowly deenergizes and at armature 429 opens the circuit for relay 418 which also slowly deenergizes.

The connection of earth to lead 503 by way of resistance 495 completes a circuit which extends over armature 522 and its back contact, back contact and armature 513, back contact and armature 517, winding of relay 531 to battery. The parallel circuit extending to wiper 541 will be without effect if this

wiper is in eighth position as in the case described. If, however, less than the full number of digits has been sent so that wiper 541 is connected to a storage relay, the operation of this relay and of relay 514 in series with it is prevented by resistance 495. Relay 531 energizes; at armature 532 completes a circuit for relay 518, at armature 537 places a holding earth on lead 504 and at armatures 533, 534, 535, 536 disconnects leads 500, 501, 502, 503 from wipers 538, 539, 540, 541 respectively and at the front contacts of armatures 534 and 535 connects leads 501 and 502 through to the impulsive leads 550 and 549. It will be understood that earth is connected to lead 504 at armature 537 before it is removed at armature 427; consequently all the apparatus dependent on this earth is maintained operated. Relay 518 energizes when its circuit is completed; at armature 519 opens the circuit over lead 553 for the storage relays so as to prevent the accidental operation of any which have not yet been energized and at armature 520 opens a circuit over leads 547 and 548 for restoring the impulse sender to normal in the case of premature release. From the earth connection at armature 532 a circuit is also completed over lead 542, back contact and armature 602, armature 608 and its back contact, back contact and armature 641, armature 644 and its back contact, lead 650, armature 753 and its back contact, lead 649 and in parallel to the rotary magnets 645, 646, 647 of the code switches which accordingly commence hunting.

These code switches are preferably 25 point rotary line switches of well known type and hence each will be able to take care of 25 codes. Consequently if it is necessary to use a larger number, a number of code switches must be provided and they are then arranged to be started up and to hunt simultaneously. Associated with each code switch is a shunt field relay such as 600, (three of such relays being shown in the drawings, Fig. 6) it being understood that if more were provided they would be connected up in a similar manner; for instance back contacts of further shunt field relays would be included between armatures 641 and 644 as indicated by the portion shown dotted.

The earth potential on lead 542 also extends over back contact and armature 783 (Fig. 8) through the winding of relay 759 and interrupter 784 to battery. The interrupter 784 is arranged to control the generation of impulses at the rate normally employed for operating the automatic switches, i. e. about 10 per second. When, therefore, interrupter 784 closes its contacts, relay 759 is energized; at armature 760 it opens a point in the bridge across the impulsive leads 549 and 550 and at armature 761 completes a circuit for the driving magnet 780 of the impulse control switch. Upon the subsequent

deenergization of relay 759, magnet 780 is deenergized and thereupon operates to advance the wipers 757 and 758 one step, whereupon a circuit is completed by way of earth at the 5 multiplied contacts in the bank of wiper 758 and said wiper for relay 762.

Relay 762 upon operating, at armature 763 prepares a circuit for stepping magnet 710 of the sender control switch, at armature 764 10 opens another point in the bridge across the impulsing leads, at armature 765 prepares a circuit for relay 860 and at armature 766 connects earth to wiper 757 by way of back contact and armature 859. It will be noted 15 that the operation of both contacts 760 and 764 is at present ineffective to send impulses over the outgoing trunk line since the impulsing leads 549 and 550 are at present bridged by armature 756 and its back contact.

20 In response to the subsequent energizations and deenergizations of relay 759, the wipers 757 and 758 are stepped round at the rate of roughly 10 steps per second. In the meantime, it will be remembered, the code switches 25 are hunting to find the contacts which have been marked by the operation of the first, second and third storage relay groups as above described. Since as previously mentioned, the code switches would preferably 30 be ordinary rotary line switches with 25 contacts in the bank and as they are hunting freely they would describe a complete revolution over the whole 25 contacts in less time than it would take the impulse control switch 35 to take 10 steps under the control of the interrupter 784. Consequently in the ordinary course when the first three digits set up by the operator correspond to an exchange code, the code switches will have found the 40 marked contacts before the impulse control switch has taken 10 steps. As this is the normal case, it will be considered first.

As may be seen from Figure 6, contacts 45 621, 622, and 623 accessible to the first code switch are connected up to correspond with the code 876, i. e. they are connected respectively to leads 587, 574, 578; hence when the wipers 615, 616 and 617 arrive on these contacts, a circuit is completed for both windings of the shunt field relay 600 which circuit extends as follows: earth, armature 532 50 and its front contact, lead 354, armature 567 and its back contact, armature 568 and its front contact, armature 569 and its front contact, lead 587, contact 621, wiper 615, right hand winding of relay 600, wiper 616, contact 622, lead 574, over the contacts of the second storage relay group, armature 572 to battery and for the other winding from earth at 55 armature 577, contacts of the third storage relay group, lead 578, contact 623, wiper 617, left hand winding of relay 600 to battery over the previously traced circuit. The shunt field relays such as 600 and 606 are so constructed that they only operate their arma-

tures when they are energized over both windings together by current in a certain direction. Consequently the relay 600 will 70 only be energized when battery is connected to wiper 616 of the associated code switch

and earth to both wipers 615 and 617. Thus there is no possibility of the relay 600 being energized by a code similar to but not identical with that for which it is set, for instance with two digits the same. Shunt field

75 relay 600 upon operating, at armature 602 opens the energizing circuit of the driving magnets thereby stopping its own associated code switch and all the others, at armatures

603, 604 and 605 connects up wipers 618, 619 80 and 620 and at armature 601 completes a circuit over lead 648, for relay 857. Relay

857 upon operating, at armature 858 connects earth over front contact and armature 765 to contact 782 in the bank of wiper 757 85 and at armature 859 connects wiper 757 to the winding of relay 767 instead of to earth. Consequently when the wiper 757 engages 90 with the contact 782, which will happen very shortly after the energization of relay 857, a

circuit is completed from earth, front contact and armature 858, front contact and armature 765, bank contact 782, wiper 757, armature 859 and its front contact, winding of relay 767 to battery. Relay 767 upon operating, at armature 769 completes a locking

circuit for itself dependent upon armature 766, at armature 770 completes a circuit for effecting the automatic rotation of the wipers of the impulse control switch to their

home position, at armature 783 opens the circuit of impulsing relay 759 and at armature 768 completes a circuit for relay 751. The circuit of rotary magnet 780 extends

from battery, winding of magnet 780, interrupter contact 781, front contact and armature 770, wiper 758 to earth at the multiplied contacts in the bank; wipers 757 and 758

are thus rotated until wiper 758 engages contact 785, which is left dead. When this occurs the circuit for relay 762 is opened and it deenergizes after a short interval owing to its slow to release characteristic. When

armature 766 leaves its front contact, the locking circuit for relay 767 is opened and it also commences to deenergize slowly. When relay 767 has completely deenergized,

the circuit for impulsing relay 759 is again completed and a fresh rotation of the impulse switch commences.

Relay 751 is energized when its circuit is completed at armature 768 and at its armature 754 completes a locking circuit for itself to the earth on lead 542, at armature

752 places earth on wiper 700 of the sender control switch at armature 753 connects lead 650 to the lead 788 which serves no useful purpose in the present instance, at armature 755 prepares a circuit over lead 787 for magnet 710 and at armature 756 removes one

120

125

130

of the shunts around armature 760 so that this armature may now be effective in sending impulses out to the distant automatic switches. Owing to the operation of armature 752, a circuit may be traced from earth at back contact and armature 752, lead 786, wiper 700 and the first contact in its bank, lead 704, armature 863 and its back contact, lead 651, armature 611 and its bank contact, armature 605 and its front contact, wiper 620, contact 626, lead 632 to terminal 711 on the left hand side of the intermediate distributing frame, hereafter referred to as the I. D. F.

Suppose in the present instance that the code 876 set up by the operator is to be converted into 395 for operating the appropriate switches: In that case terminal 711 will be cross connected to terminal 793 on the right hand side of the I. D. F. so that earth will be extended over lead 743 to the terminal 787 corresponding to the digit 3 in the bank of wiper 757.

In connection with the operation of the impulse control switch, it should be pointed out that on the first opening of contact 760 after the switch leaves its normal position this contact is shunted by contact 764 since the relay 762 has not yet operated, but that further operations of contact 760 result in the production of interruptions of the trunk circuit since the parallel contacts 764 and 765 are now both open. The circuit across the outgoing trunk may be traced as follows: from the upper talking conductor 336 over the normally closed springs controlled by relays 315, 314 and 313, front contact and armature 316, lead 405, front contact and armature 441, wiper 472, lead 502, armature 535 and its front contact, lead 549, armature 760 and its back contact, lead 550, front contact and armature 534, lead 501, wiper 471, armature 440 and its front contact, lead 407, armature 317 and its front contact, normally closed springs controlled by relays 313, 314 and 315 to the lower talking conductor 337.

Upon the de-energization of relay 767, the impulsing relay 759 will again operate to step the wipers 757 and 758 round and to open contact 760 until three impulses have been sent out, whereupon wiper 757 will engage with contact 787. A circuit will then be completed from armature 752 as previously traced over wiper 757, armature 859 and its front contact, winding of relay 767 to battery. Relay 767 therefore operates with the results previously described, namely, that the circuit of the impulsing relay 759 is opened and the impulse control switch is automatically returned to its normal position, whereupon relays 762 and 767 deenergize.

It will be observed that as soon as relay 762 energized the second time a circuit was completed from earth over wiper 758, armature 763 and its front contact, armature 755 and

its front contact and lead 787 for the driving magnet 710 of the sender control switch. This magnet thus remains energized as long as the wiper 758 continues to find earth but as soon as it reaches the dead contact 785 or the corresponding contact in the other half of the bank, the magnet 710 will be deenergized and will operate to advance the wipers 700, 701, 702 and 703 one step into engagement with the next set of bank contacts. The earth from armature 752 now extends over lead 786, wiper 700, lead 705, armature 862 and its back contact, lead 652, armature 610 and its back contact, armature 604 and its front contact, wiper 619, contact 625, lead 631 to terminal 712 on the left hand side of the I. D. F. According to the assumption made above, this terminal is cross connected to terminal 799 on the right hand side of the I. D. F.; consequently, the earth is extended over lead 749 to the contact corresponding to the digit 9 in the bank of wiper 757. It should be mentioned that the second half of the banks of wipers 757 and 758 is connected up in the same way as the first half, so that the switch has two normal positions from either of which the operation is the same. Upon the deenergization of both relays 762 and 767 relay 759 will be again energized and will operate intermittently to control the stepping of the wipers 757 and 758 over their respective banks and to generate impulses for transmission over the outgoing trunk line. In this case it will be seen that nine impulses will be sent out before relay 767 is again operated and the generation of impulses, stopped.

When relay 762 deenergizes the circuit for magnet 710 is again opened and upon deenergizing it operates to step the wipers of the sender control switch into their third position in which wiper 700 is connected to lead 706. A circuit from earth at the front contact and armature 752 may now be traced over lead 786, wiper 700 in third position, lead 708, armature 861 and its back contact, lead 653, armature 609 and its back contact, armature 603 and its front contact, wiper 618, contact 624, lead 630 to terminal 713 on the left hand side of the I. D. F. This on the assumption made above will be cross connected to terminal 795 on the right hand side; consequently the earth connection extends over lead 745 to the contact corresponding to the digit 5 in the bank of wiper 757. In this case, therefore five impulses will be sent out over the outgoing trunk line, after which relay 767 will be energized and will operate to stop the sending of further impulses and to effect the automatic rotation of the wipers of the impulse control switch on to their normal position.

Upon the release of relay 762 and the consequent opening of contact 763, magnet 710 is deenergized and the sender control switch

is moved a further step. A circuit is now completed from earth, armature 722 and its back contact, back contact and armature 728, fourth contact in the bank of wiper 702 and said wiper to magnet 710 by way of its interrupter contact; consequently the wipers 700, 701, 702 and 703 are moved a further step. In the fifth position of the wipers a circuit is again completed over armature 721 and 727 so that the switch moves into sixth position. In this position also magnet 710 is energized from earth at armature 720 over wiper 702; consequently the wipers are moved into the seventh position. Thereupon wiper 702 encounters a permanent earth connection so that the sender control switch is moved into its eighth position.

In this position the earth from armature 752 extends over wiper 700 in eighth position and lead 583 to the first contact of the fourth storage relay group and thence over the appropriate operated contacts to lead 579 which is connected to lead 745 and thus to the bank of wiper 757. Hence by the operation of relays 759, 762 and 767 in the manner previously described, five impulses will be sent over the outgoing trunk line. Upon the de-energization of relay 762 when the impulse control switch reaches its normal position, the sender control switch is moved on one step in preparation for the sending of the second numerical digit. In this case earth will be connected to lead 580 and hence to lead 744 and four impulses will be sent out. In a similar manner two further trains consisting of three and two impulses will be sent out.

The sender control switch is thus stepped on into its twelfth position in which earth is connected over wiper 700 and lead 790 direct to lead 588, in consequence of which a further train comprising a single impulse is sent out, this train being additional to the number set up by the operator on the keys. This additional impulse is to indicate, in case the call is going to an operator at a call indicator position, that the call in question has come from a mechanical tandem exchange and not direct from an automatic subscriber. In case the call were going direct to an automatic subscriber, this extra impulse would have no deleterious effect but would simply be absorbed. It will be understood however that this call indicator impulse is by no means essential to the proper working of the system and that in many cases it may be desirable to omit it altogether.

Upon the termination of this extra call indicator impulse, the wipers of the sender control switch will be moved into the thirteenth position, whereupon the following circuit is completed: earth, wiper 703, lead 546, upper winding of relay 521 to battery. Relay 521 thereupon operates at armature 523 opens the circuit of relay 531 and at armature 523 re-

moves earth at the front contact of armature 537 from lead 504 and hence from lead 403, in consequence of which the sender guard lamp 476 is extinguished and relay 422 and relay 312 deenergize. Upon the consequent opening of contact 303, earth is removed from lead 404 whereupon relay 423 deenergizes and all the apparatus associated with the particular outlet which has been used is then released. Relay 521 also at its armature 524 closes another point in the chain circuit over lead 506 for moving on the outlet finder in case all the senders in the group are busy, this operation becoming effective after the opening of contact 530.

Upon the deenergization of relay 531, relay 525 is released by the removal of earth at armature 537, as are also all the operated storage relays which were locked up to lead 552. Furthermore at contact 532 the circuit of relay 518 is opened and earth is removed from leads 554 and 542. In consequence of the removal of earth from lead 554 and of the release of the storage relays, the shunt field relay which has been operated is deenergized and in consequence of the removal of earth from lead 542, the relay 751 is released and the further operation of the impulse control switch through relay 759 is prevented. Relay 857 is deenergized when its circuit is opened at contact 601 on the release of the shunt field relay 600.

Upon the deenergization of relay 525, at armature 526 earth is again connected to lead 504 to prevent the sender being seized again before it has completely restored to normal and a circuit is also completed for release magnet 508 of the transfer switch by way of the off normal contact 509, so that this switch is returned to normal. At armature 527 earth is connected to lead 543 and thence to the multiplied contacts in the bank of wiper 701 so that the sender control switch is automatically restored to its normal position. As long as the sender control switch is in an off normal position, this earth extends over lead 544 and armature 528 and its back contact to the lower winding of relay 521 and will maintain this relay energized so as to prevent the sender being taken into use before it has regained its normal position. The engagement of armature 529 with its back contact serves no useful purpose in the present instance since the wiper 758 to which it is connected is moved to its normal position before the releasing operation commences. The armature 530 opens a point in the chain circuit for busying the group of senders but as this armature has been shunted by armature 524 as previously described this operation is also without effect.

When wiper 701 reaches its normal position, release relay 521 will receive no more current and will consequently deenergize.

All the operated apparatus has then been released, and the sender may be taken into use for the setting up of a new connection.

In the trunk circuit the deenergization of relay 312 completed the speaking leads and the wanted party would be notified in the usual manner. When he replies the direction of current flow is reversed over the speaking leads in consequence of which polarized relay 342 is now able to operate and at its armature 343 it then connects the retardation coil 345 to lead 302 so as to give the A operator answering supervision. Relays 338 and 339 remain energized for the remainder of the connection until the A operator removes her plug. When this occurs, relay 339 is deenergized; at armature 340 it opens the circuit of relay 338 and at armature 341 extinguishes the trunk busy lamp 323, thus indicating to the B operator that the junction line is idle and may be used for another call.

Consider now the case in which owing to some mistake on the part of the operator, she has set up a number the first three digits of which do not correspond to any exchange code, in which case, unless special provision were made, the code switches would continue hunting without result.

According to the arrangement shown, however, if no shunt field relay is operated by the time wiper 757 comes into engagement with contact 782, the following circuit is completed; earth, armature 765 and its front contact, back contact and armature 858, normally closed springs controlled by armature 864, winding of relay 860 to battery. Relay 860 accordingly operates, at its armature 864 locks itself up to lead 542, at armature 865 completes a circuit for relay 857 and at armatures 861, 862 and 863 transfers the leads 706, 705 and 704 from the first three contacts in the bank of wiper 700 to leads 801, 802 and 803 respectively which leads are connected to terminals 806, 805 and 804 on the left hand side of the I. D. F. Relay 857 operates quickly when its circuit is completed and a circuit may then be traced from earth at the front contact of armature 858 and said armature, front contact and armature 765, bank contact 782, wiper 757, armature 859 and its front contact, winding of relay 767 to battery. Relay 767 accordingly operates, at its armature 783 opens the circuit of the impulsing relay 759, at armature 770 completes a circuit for restoring the impulse control switch to its normal position, at armature 769 completes a locking circuit for itself and at armature 768 completes an energizing circuit for relay 751. This relay then operates and initiates the sending of impulses in the manner previously described.

It will probably be desirable to arrange for a dead number call to be routed to an operator's position in which case the terminals 804, 805 and 806 will be cross connected to appro-

priate contacts on the right hand side of the I. D. F., so as to send the requisite code. In case less than three digits should be required to reach the dead number operator's position, suitable cross connections will be made to the first three contacts in the bank of wiper 702 of the sender control switch. For instance, suppose that only two digits are required; in that case terminals 804 and 805 will be cross connected respectively to the terminals 70 on the right hand side of the I. D. F. corresponding to these two digits, while terminal 806 will be connected to contact 809. Under these circumstances when the sender control switch is moved to its third position after the two digits have been sent, wiper 702 will find earth over contact 809 and wiper 700 and the switch will be immediately moved into fourth position and on into eighth position as previously described. If only one digit is required for reaching the operator's position, terminal 805 will be cross connected to connect 808 in which case the sender control switch will move on automatically from position 2 to position 8. For a call of this nature, it is clearly not necessary for any numerical digits to be sent and the impulse sender may be released as soon as sufficient digits have been sent to reach an operator. This is taken care of over lead 788 since when the sender control switch arrives in position 8 a circuit may be traced as follows: earth, armature 532 and its front contact, lead 542, back contact and armature 602, armature 608 and its back contact, back contact and armature 641, 90 armature 644 and its back contact, lead 650, armature 753 and its front contact, lead 788, eighth contact in the bank of wiper 703 and said wiper, lead 546, upper winding of relay 521 to battery. Relay 521 is thus operated 100 and initiates the release of all the operated apparatus in the manner previously described.

For calling an operator direct, for example for toll calls or information, the single digit 0 is sent, in which case it will clearly be necessary for the B operator to press the start key before the sending of impulse will commence. When earth is connected to lead 554 as a consequence of the operation of relay 531, this earth is extended over the operated armatures of relays 565 and 566 to the 0 digit relay 606. This thereupon operates, at armature 608 opens the starting circuit for the code switches so as to prevent useless hunting, at 115 armature 607 completes a circuit for relay 857 and at armatures 609, 610, 611, connects the first three contacts in the bank of wiper 700 by way of leads 612, 613, 614 to special terminals on the left hand side of the I. D. F. From these suitable cross connections are 120 made to the right hand side to control the generation of the trains of impulses necessary to route the call to an operator. Clearly 125 in this case also arrangements may readily be 130

made for sending only one or two digits and only comparatively simple additional connections would be required if it should be necessary to send four or five digits. This 5 will be more readily understood from the description of the various special code relays which will now be given.

It may happen in exceptional cases that it 10 will be desirable to send either more or less than the three digits for an exchange code which are provided for in normal working or that the special code is such that no numerical digits are required. From what has been 15 said already in connection with dead number calls, it will be clear that if less digits are required a proper operation of the various switches may be effected by cross connections from the I. D. F. terminals connected to the contacts of the code line switches to the requisite 20 contact or contacts in the bank of wiper 702.

Consider first the case in which five code digits are to be sent: This case is taken care of by relay 723. Suppose that the first code 25 switch finds the marked contacts and comes to rest on contact 629 and its associated contacts. When the start key is pressed or the corresponding automatic operation has taken place, the following circuit will be completed: 30 earth, front contact and armature 752, lead 786, wiper 700 and the first contact in its bank, lead 704, armature 863 and its back contact, lead 651, armature 611 and its back contact, armature 605 and its front contact, 35 wiper 620, contact 629, lead 635, normally closed springs controlled by armature 726, winding of relay 723 to battery. Relay 723 operates, at armature 726 locks itself up to the earth on lead 542, at armatures 724, 725 40 and 729 prepares circuits to terminals 810, 811 and 812 on the left hand side of the I. D. F., and at armatures 728 and 727 removes earth from the fourth and fifth contacts in the bank of wiper 702.

45 It will now be seen that the first digit sent out will be in accordance with the terminal on the right hand side of the I. D. F. which is cross connected to terminal 812. The second and third digits are determined by connections from the contacts engaged by wipers 619 and 618 which lead to terminals on the left hand side of the I. D. F. from which the required cross connections are made. The fourth digit will be determined by the cross 55 connection from terminal 810 while the fifth digits will similarly be determined by the cross connection from terminal 811. After the five digits of the converted exchange code have been sent out, the numerical digits will 60 be transmitted in the manner previously described and the subsequent releasing operation is as before.

In case the three digits of the exchange code set up by the operator are to be converted 65 into six digits the general arrangements are

similar. In this case it is assumed that the first code line switch comes to rest on contact 628 and its associated contacts, whereupon, when the start key is pressed, a circuit is completed for relay 714. This relay energizes, 70 locks itself up at armature 719 and at armatures 715, 716, 717 and 718 prepares circuits for suitable cross connections in a manner similar to that described for relay 723. The only difference is that an extra armature is 75 provided to connect up the terminal which controls the sixth digit and that earth is removed at armature 720 from the sixth contact in the bank of wiper 702 so as to prevent the switch running through this position. The remaining operations take place in a manner which will be readily followed from what has gone before.

The functions and method of operation of relay 730 will now be described. This relay 80 will be energized when contact 532 closes if the first code switch has come to rest on contact 627 and its associated contacts. Relay 730 upon operating, at armature 732 locks itself up to lead 542 and at armature 731 connects earth to terminal 813 on the left hand side of the I. D. F. This terminal is connected according to requirements to one of the contacts in the bank of wiper 703 and permits switching through and the release of 85 the impulse sender after any desired number of digits have been sent. For instance if terminal 813 is cross connected to terminal 814 relay 821 will be energized and the impulse sender released after five digits have been 90 transmitted.

It should be noted also that by suitable cross connections from the left hand side of the I. D. F. to the switching terminal 815, it is 95 possible to switch through as soon as the exchange code has been transmitted or after one or more numerical digits have been sent. If such a connection is made however it is necessary to sacrifice one terminal which could be used for controlling the generation of a train 100 of impulses, so that in some cases it will be more desirable to effect the same result through relay 730 which can be common to several codes.

In case the operator makes a mistake in 110 setting up the wanted number and discovers it before the complete number has been set up, that is, before the operations corresponding to the pressing of the start key have taken place, she is enabled to cancel the digits already set up by pressing the cancel key 484. This brings about the operation of relay 448 which at its armature 450 completes a circuit for relay 447. At its armature 451 removes earth from the holding lead 504, and at its armature 456 removes earth from wiper 455 so as to prevent another operator from 115 seizing this set of impulse sending equipment during the momentary removal of earth from test wiper 474. Relay 477 energizes when its 120 125 130

circuit is completed and at armature 449 opens the circuit of relay 448 and connects it self up in dependence on the key 484. Relay 448 being slow to release remains operated 5 for a short while which is the same however long the key is pressed. The removal of earth from lead 504 releases all the operated storage relays and also relay 525 which by closing its contact 526 effects the return of 10 the transfer switch to normal. The operator may now proceed to set up the right number and in this case will use the same outlet and impulse sender.

In case the sending of impulses has actually 15 commenced before the operator discovers her mistake, she will press the busy or cancel key associated with the trunk line which has been taken into use, the effect of this being to open the locking circuit for the relays 338 and 312. 20 Upon the deenergization of these relays the circuit of relay 531 is opened at armatures 321 and 328 so that this relay deenergizes and releases all the operated apparatus in the set of impulse sending equipment in the manner 25 previously described. The operator will then press the assignment key 304 again whereupon another impulse sender set will be seized over another outlet (since the outlet finder was stepped on when impulse sending 30 commenced) and the connection may be completed in the ordinary way. If the impulse control switch should be in an off normal position it would be returned to normal by the 35 operation of its stepping magnet in a circuit extending over back contact and armature 520. The relay 521 will be operated during this movement as also during the return of the sender control switch to normal and will maintain the impulse sender busy until these 40 movements are completed.

The emergency order wire key is provided in order to enable the inter-exchange junction line to be used as an order wire in case of necessity. When this key is operated, the 45 connections of conductors 302 and 303 to the trunk circuit relays are broken at springs 346 and 348 and these conductors are connected at springs 347 and 349 to the leads 351 and 352 which can be extended to the operator's head set. At spring 350 a circuit is completed for the trunk busy lamp 323 which is thus lighted to indicate to the operator that the trunk line cannot be used for outgoing 50 connections.

55 Should a junction line be out of order and therefore not available for use, the operator will press the busy key associated with that line. In this case the only effective operation will be the completion of the circuit for the 60 busy lamp 323 at springs 350, so that the operator is notified that the line must not be used. Inspection of Fig. 2 will show, however, that should the operator assign the line in error it will be impossible for an impulse 65 sender to be associated with it permanently

and the lamp 322 will not light in the ordinary manner.

In case one of the outlets should be out of order, it will be necessary to operate the associated sender disconnect key. At the left 70 hand spring of this key the energizing circuit for relay 420 is opened at spring 462 and at spring 461 earth is connected to the corresponding contact in the outlet finder so as to prevent this particular outlet being taken 75 into use. At the right hand spring of the key a circuit is completed for the sender guard lamp 476 at the spring 463 and at spring 464 the energizing circuit for the relay 80 312 is opened.

The case when all the senders accessible to a sender selector are busy is taken care of by a chain circuit extending over contacts 524 and 530 in parallel and over similar contacts on other impulse senders in the group to 85 earth. When all the impulse senders of a group are in use therefore, a circuit is completed for relay 421, which upon operating, at armature 435 connects earth to armature 466, at armature 434 opens the energizing circuit 90 of relay 420 and at the front contact of this armature connects earth to the contact corresponding to this outlet in the bank of the outlet finder. One effect of the connection of earth to the contact with which wiper 460 95 is in engagement is to complete a circuit for relays 410 and 409 in series. Relay 410 energizes and at its armature 466 opens a point in a circuit for the driving magnet 467 and relay 409 also energizes a short while after and 100 at armature 465 closes another point in this circuit which consequently does not become operative. The earth connection through relay 410, which is of very low resistance, also extends over lead 400, armature 311 and its 105 resting contact, chain of similar contacts on other assignment relays, armature 310 and its resting contact lead 401, interrupter contact 468 to driving magnet 467. Driving magnet 467 accordingly operates and advances the switch wipers one step into engagement with the next set of contacts. In case all 110 the senders accessible by way of this outlet also are busy, there will be earth on the contact with which wiper 460 is now in engagement and the switch will continue to hunt until an idle outlet is found over which the connection can be completed.

It might happen in some cases that the outlet which has been preselected has access to 115 only one idle sender and that while the associated sender selector is hunting for this sender it is taken into use from some other operator's position. It is clear that unless special provision were made the sender became free 120 and unnecessary waste of time and wear of the switch would be occasioned. In this case also therefore it is necessary for the outlet finder to step on to find a new outlet but the circuit traced above is no longer operative 125 130

since it is open at one of the chain contacts; however, this condition is taken care of by relay 410. When the assignment key is pressed, relays 409 and 410 are energized as previously described in series with relay 420 and the sender selector commences to hunt. If now all the senders in the group become busy, relay 421 operates and substitutes an earth connection at armature 429 for the connection to battery through relay 420. Relay 410 is thereupon short circuited and at its armature 466 completes a circuit from earth, front contact and armature 435 of relay 421, armature 466 and its back contact, armature 465 and its front contact, interrupter contact 468 to driving magnet 467. The outlet finder is thus automatically stepped on to find a free outlet and unnecessary hunting of the sender selector and waste of the operator's time are avoided.

It may be desirable at this point to explain the precise nature and operation of the lamp signals which are provided to indicate to the operator the progress of the connection. As has already been explained, the operator holds the assignment key pressed until the assignment lamp 322 lights. If the A operator has not already plugged in, the lamp 322 will glow intermittently under the control of the flashing interrupter 333, and will continue to flash until the A operator does plug in, after which it will glow steadily until the sending of impulses commences. At the same time the sender guard lamp 476 will light and glow steadily to indicate that an outlet is in use. As has been pointed out, if the A operator is a trifle late in plugging in, this operation will control the starting of the sending of impulses and consequently in this case the lamp 322 will continue to flash until it is extinguished.

The trunk busy lamp 323 will always be lighted when the A operator plugs in; in case the B operator should not yet have pressed her assignment key, the lamp will flash until the key is pressed and an idle impulse sender is found, whereupon it will glow steadily and continue to do so until the connection is taken down. By means of these lamp signals the B operator is kept fully informed at the progress of the connection except that she is not given answering supervision when the calling subscriber replies as this is clearly unnecessary. The sender guard lamp 476 will remain lighted as long as the particular outlet is in use or the sender disconnect key is operated.

A description may now be given of the apparatus shown in the lower part of Fig. 3, the purpose of which is to obviate the possibility of two operators seizing the same impulse sender at the same time. The relays such as 408 are individual to each operator's position and each is connected to the lead corresponding to lead 400 so that it will energize when-

ever any assignment key in the position is pressed. Relay 408 controls two armatures 452 and 453 in chain circuits which include contacts controlled by the relays similar to 408 associated with all the other positions having access to the same group of impulse senders. The former of these circuits comprises a closed series chain circuit extending through the armatures and back contacts,

while the armatures are also connected to appropriate contacts in the bank of wiper 455. The front contacts of these armatures extend to armatures such as 432 and are thus included in the energizing circuits of the cut-off relays such as 419. It will be remembered

that the circuit for relay 419 was traced from earth at resting contact and armature 492, chain of similar contacts on other cancelling relays, armature 456 and its resting contact, wiper 455 and the contact with which it is in engagement, armature 452 and its working contact to relay 419. It will be seen that if only one relay such as 408 is operated at a time and the wiper 455 is in a different position from that shown, a circuit for relay 419 will still be completed over the armatures such as 452 and their back contacts. When, however, there is more than one relay 408 operated at a time, in which case wiper 455 will be rotating, as about to be explained, circuits for relays such as 419 will only be completed in turn as wiper 455 comes into engagement with the contact connected to the armature controlled by the particular relay. By this means it is made certain that no two operators can possibly seize the same impulse sender owing to their respective sender selectors coming to rest at the same instant on multiplied contacts. In order to arrange that the wiper 455 shall rotate when at least two operators press their assignment keys simultaneously, but not otherwise, the second chain circuit including contacts 453, 493 and 494 is made use of. It will be apparent from

inspection of the drawing that as long as none or only one of the relays 408 is operated, a circuit will not be completed for the driving magnet 491 of the wiper 455 but as soon as two or more of these relays are operated, a circuit is completed and consequently the wiper 455 is started up. By this means unnecessary rotation of wiper 455 is avoided and the life of the switch is correspondingly lengthened. The relays 408 will only be operated as long as the operator keeps her assignment key pressed and thus it is by no means unlikely that even with a large number of operators, only one may be pressing an assignment key at any particular instant. The earth connection to the wiper 455 is taken through additional contacts on the cancellation relay such as 448 in order that if an operator presses her cancel key 484 whereupon earth is momentarily removed from the multiple test contact in the bank of wiper

474, no other operator will be able to seize the impulse sender which has been taken into use and it can be used again for setting up the proper number and the transmission of 5 the required impulses.

It has beeен arranged in the particular embodiment of the invention shown that the sending of impulses does not commence until the A operator plugs in, since this is in general 10 desirable. It should be understood, however, that this is not essential to the working of the arrangement and that by eliminating the starting contacts on the relay 338 and substituting direct connections, the starting of 15 the generation of impulses may be placed under the sole control of the B operator at the tandem exchange.

Having now particularly described and ascertained the nature of our said invention and 20 what manner the same is to be performed, we declare that what we claim is:

1. In a multi-office telephone system, an operator's switchboard, a subscriber's line and means for extending the same to said 25 switchboard, a key set at said switchboard, a register sender including registers operated under the control of said key set for storing a plurality of digits, a translating device in 30 said register sender to translate the stored digits indicative of the office in which the called line terminates, and means for operating the sending portion of said register sender under the control of said translating device to transmit the series of impulses necessary to trunk the call to the called office, 35 and for operating said sending portion under the control of the register independent of said translating device to transmit the digits necessary to extend the connection to the desired called line.

2. In a telephone system, an operator's switchboard, a key set at said switchboard, a register sender including registers operated under the control of said key set for storing 45 the digits of a called telephone number, a translating device in said register sender to translate the stored digits indicative of the office in which the called line terminates, and means for operating the sending portion of said register sender under the control of said translating device to transmit the series of impulses necessary to trunk the call to the called office and for operating said sending portion to transmit untranslated the remaining digits stored on said registering device.

3. In a telephone system, an operator's key set, a register sender for storing a plurality of digits under the control of said key set, means for effecting the storing operation comprising a plurality of circuits closed by 50 said keys singly and in combination, a translating device operated under the control of the portion of said register that records certain ones of said digits, and a sender responsive to control from said translating device

and subsequently to control from the remaining portion of the register independent of said translating device to transmit the required series of impulses.

4. A register sender including a plurality of storage relay sets for storing a like plurality of digits, a translating device controlled by certain ones of said relay sets, and a sending device controlled by said translating device and by the remaining ones of said relay sets independent of said translating device.

5. In combination, a register sender, an operator's switchboard, a controlling key set at said switchboard, a registering device comprising storage relay sets included in said register sender and responsive to the operation of said key set to register telephone numbers, a sending device included in said register sender, and a translating device controlled by the registration on said registering device 85 indicative of the called office to control said sending device to transmit impulse series representing digits that differ in number and value from those controlling the translating device.

6. In a telephone system, an operator's switchboard, a key set at said switchboard, a register sender controlled by said key set to register and retransmit telephone numbers, and means in said register sender responsive 95 to a set up on said key set which does not correspond to a working telephone number for transmitting a special number having no numerical relation to the number recorded on said key set.

7. In a telephone system, an operator's switchboard, a key set at said switchboard, a register sender at said switchboard including a plurality of separate digit registers, means including a step by step switch for directly connecting said key set with said digit registers successively, and a second step by step switch for associating the sending portion of said register sender with said digit registers successively.

8. In a telephone system, a register sender for transmitting digit impulses to control automatic switches, said register sender including a plurality of registering devices and a sending device, a translating device having 115 a number of positions each corresponding to a separate composite setting of said registering devices, means for setting said registering devices and for starting said translating device, and means effective at the end of a 120 predetermined time interval in case the translating device has not found a position corresponding to the instant setting of said registering devices for operating the sending portion of said register sender to transmit a pre- 125 determined combination of digit impulses.

9. In combination, a plurality of registering devices and means for setting them to record telephone numbers, a translating device having positions corresponding to cer- 130

tain possible settings of said registering devices, and time controlled means operative at the end of a predetermined time interval in case said translating device is unable to 5 find a position corresponding to the instant setting of said registering devices.

10. In a telephone system, an operator's key set operable in accordance with the several digits in a telephone number, a register sender controlled by said key set to generate impulses representing a translation of a portion of the number and for generating further impulses representing the remaining portion of the number, and a train of automatic switches 15 responsive to the generated impulses to complete the connection to the line bearing the called number.

11. In a telephone system, an operator's key set operable in accordance with the several digits in a telephone number, a register sender controlled by said key set to generate impulses representing a translation of a portion of the number and for generating further impulses representing the remaining portion 25 of the number, and a free hunting translating switch for responding to the portion of the number to be translated included in said register sender.

12. In a telephone system, an operator's key set operable in accordance with the several digits in a telephone number, a register sender controlled by said key set to generate impulses representing a translation of a portion of the number and for generating further 35 impulses representing the remaining portion of the number, a free hunting translating switch for responding to the portion of the number to be translated included in said register sender, and means effective upon a complete registration of the called number for 40 starting said translating switch and the sending portion of said register sender and for preventing the sending of impulses until the hunting operation of said translating switch 45 has taken place.

13. In combination, registering devices comprising a plurality of relay groups and a translator switch, means for setting said devices by operating the relays in the groups 50 in certain combinations, and means for starting said translator switch and for giving it a single hunting movement to bring it into a position corresponding to the instant composite settings of the relays of said registering devices.

14. A register sender including a plurality of storage relay sets for storing a like plurality of digits, a translating device controlled by composite settings of certain ones of said sets, and a sending device controlled by said translating device.

15. In a multi-office telephone system, a sender for transmitting different pluralities of digits corresponding to office codes, a switch 60 for controlling said sender and having as

many code digit positions as there are digits in the longest office code, means normally effective to cause said switch to skip certain ones of said code digit positions, and means for disabling said skipping means in case a call is to be extended requiring the longest office code. 70

16. In a multi-office telephone system, a sender for transmitting different pluralities of digits corresponding to office codes, a switch for controlling said sender and having as many code digit positions as there are digits in the longest office code, means normally effective to cause said switch to skip certain ones of said code digit positions, means for disabling said skipping means in case a 80 call is to be extended requiring the longest office code, and means for partially disabling said skipping means in case another office code is transmitted. 75

17. In a multi-office telephone system, a sender for transmitting different pluralities of digits corresponding to office codes, a switch for controlling said sender and having as many code digit positions as there are digits in the longest office code, means normally effective to cause said switch to skip certain ones of said code digit positions, a translating switch, means for setting said translating switch in a position representing the longest office code, and means operative responsive to the setting of said translating switch for disabling said skipping means. 90 95

18. In a multi-office telephone system, sender for transmitting different pluralities of digits corresponding to office codes, a switch having a position for each digit of an office code by means of which said switch controls said sender, means normally effective to cause said switch to skip certain ones of said digit positions, and means for disabling said skipping means when a certain office code is transmitted. 100 105

19. In a multi-office telephone system, sender for transmitting different pluralities of digits corresponding to office codes, a switch having a position for each digit of an office code by means of which said switch controls said sender, means normally effective to cause said switch to skip certain ones of said digit position, a translating switch, and means for setting said translating switch in a certain position for causing said sender control switch to disable said skipping means. 110 115

20. In a multi-office telephone system, a sender for transmitting different pluralities of digits corresponding to office codes, a switch having a position for each digit of an office code by means of which said switch controls said sender, means normally effective to cause said switch to skip certain ones of said digit positions, and means for partially disabling said skipping means when a certain office code is transmitted. 120 125

21. In a telephone system, a register sender for transmitting digit impulses to control 130

- automatic switches, said register sender including a plurality of registering devices and a sending device, a translating device having a number of positions each corresponding to a separate composite setting of said registering devices, means for setting said registering devices and for starting said translating and sending devices, and means for stopping said translating device when 5 said sending device completes a cycle of operation in case said translating device has not found a position corresponding to the instant composite setting of said registering devices.
- 15 22. In a telephone system, a register sender for transmitting digit impulses to control automatic switches, said register sender including a plurality of registering devices and a sending device, a translating device having 20 a number of positions each corresponding to a separate composite setting of said registering devices, means for setting said registering devices and for starting said translating and sending devices, means for stopping 25 said translating device when said sending device completes a cycle of operations in case said translating device has not found a position corresponding to the instant composite setting of said registering devices, an operator's switchboard, and means effective when 30 the translating device is stopped for causing said sending device to transmit a predetermined combination of digit impulses to extend the call to said switchboard.
- 35 23. In a telephone system, a register sender, switching devices for taking said sender for use when the same is idle, a test conductor extending between said sender and the test contacts of said devices, a holding 40 relay in said sender, a circuit for energizing said relay including said test conductor, contacts on said relay for applying a guarding potential to said conductor, a sending device in said sender operable to transmit a plurality 45 of digits, a step by step switch having a set of wipers and cooperating contacts, means for advancing said switch one step after each digit transmitted by said sender, and means including one of the wipers and one of contacts of said switch for opening the energizing 50 circuit of said relay.
24. In a telephone system, a register sender, switching devices for taking said sender for use when the same is idle, a test 55 conductor extending between said sender and the test contacts of said devices, a holding relay in said sender, a circuit for energizing said relay including said test conductor, contacts on said relay for applying a guarding 60 potential to said conductor, a sending device in said sender operable to transmit a plurality of digits, a step by step switch having a set of wipers and cooperating contacts, means for advancing said switch one step after each

digit transmitted by said sender, means including one of the wipers and one of the contacts of said switch for opening the circuit of said relay thereby causing said relay to deenergize and remove said guarding potential, and means operative responsive to said last means for again applying guarding potential to said test conductor until said sender and switch have been restored to normal condition.

25. In a telephone system, a register 75 sender including registering devices for registering telephone numbers and a sending device responsive to settings of said registering devices to transmit digit impulses, hunting switches having access to said register sender, means for causing one of said switches to seize said register sender, and for subsequently operating the same, means in said sender for rendering said sender busy to the other hunting switches, and means in said 80 register sender responsive to the retransmission of the last stored digit for temporarily removing said busy condition to permit said hunting switch to free the register sender and for subsequently reapplying said busy 85 condition until the sender has been restored to its normal condition.

26. In a register sender including a sending device for transmitting the requisite number of digits to extend a connection to the 95 desired line, an output control switch for controlling said sending device, said switch having a separate position for each digit, a release wiper and release bank contacts in said switch, an intermediate distributing 100 frame, means including conductors and terminals for terminating said release bank contacts on said frame, and means including said release wiper and cross connections on said frame to said terminals for causing said 105 sender to be released after any predetermined number of digits have been transmitted.

27. In a semi-automatic telephone system, a plurality of registers for registering the digits in called numbers, an operator's key 110 set for setting said registers, a sending switch, permanent multiple connections, between the bank of said sending switch and a plurality of said registers, a translating switch controlled by the other of said registers, and a distributing 115 frame for connecting the bank of said sending switch with the bank of said translating switch.

28. In a semi-automatic system, automatic switches, a plurality of relay registers for 120 registering the office designation of a called number, other registers for registering the subscriber's digits in a called number, an operator's key set for setting all said registers, a translating switch automatically positioned in accordance with the operated position of said relay registers, and an impulse sending device controlled by said translating

ing switch and said other registers for transmitting impulses to said switches to complete a desired connection.

29. In a semi-automatic system, automatic switches, a plurality of relay registers for registering the office designation of a called number, other registers for registering the subscriber's digits in a called number, an operator's key set for setting all said registers, a translating switch automatically positioned in accordance with the operated position of said relay registers, an impulse sending device controlled by said translating switch and said other registers for transmitting impulses to said switches to complete a desired connection, and a sequence switch for shifting the control of said sending device from said translating switch to said other registers.

30. In an operator's sender, a plurality of relay registers for registering the office designations of called numbers, an operator's key set for setting said registers, a translating switch having banks, said switch automatically positioned in accordance with the operated position of said relay registers to select office codes, a sending device, and means including a distributing frame for variably connecting the banks of said translating switch with said device to determine the number of digits in the selected office code and the denomination of each digit.

31. In an operator's sender, a translating switch, said switch having a plurality of banks and wipers, registers and keys for setting said switch, a sending device for transmitting impulses controlled by said wipers, and means for rendering said wipers effective one after the other in a definite order.

32. In an operator's sender, a translating switch, said switch having a plurality of banks and wipers, registers and keys for setting said switch, a sending device for transmitting impulses controlled by said wipers, and a sequence switch for rendering said wipers separately effective to control said sending device.

33. In a semi-automatic telephone system, a series of automatic switches, a trunk line extending to the first of said switches and comprising two normally disconnected sections, operator controlled means for extending a calling line to the first of said sections, an operator's register sender, operator controlled means for connecting said sender to said trunk line at the junction of said sections, a set of keys and registers in said sender for registering the digits in the called number, means for translating certain of said digits into a set of code digits, and a sending device in said sender for transmitting series of impulses over the second section of said trunk line in accordance with the code digits and the untranslated digits to operate said switches.

34. In a semi-automatic telephone system, a series of automatic switches, a trunk line extending to the first of said switches and comprising two normally disconnected sections, operator controlled means for extending a calling line to the first of said sections, an operator's register sender, operator controlled means for connecting said sender to said trunk line at the junction of said sections, a set of keys and registers in said sender for registering the digits in the called number, means for translating certain of said digits into a set of code digits, a sending device in said sender for transmitting series of impulses over the second section of said trunk line in accordance with the code digits and the untranslated digits to operate said switches, and means responsive to the transmission of the last series of impulses for connecting the two sections of said trunk line together.

35. In a semi-automatic telephone system, a series of automatic switches, a trunk line extending to the first of said switches and comprising two normally disconnected sections, operator controlled means for extending a calling line to the first of said sections, an operator's register sender, operator controlled means for connecting said sender to said trunk line at the junction of said sections, a set of keys and registers in said sender for registering the digits in the called number, means for translating certain of said digits into a set of code digits, a sending device in said sender for transmitting series of impulses over the second section of said trunk line in accordance with the code digits and the untranslated digits to operate said switches, means responsive to the transmission of the last series of impulses for connecting the two sections of said trunk line together, and means for disconnecting said register sender to restore the same when the impulse transmission is completed.

36. In a semi-automatic telephone system, means including an operator's key set for registering all the digits in a called number, means for translating the digits which have to do with the office selection into a code in accordance with which the digits transmitted trunk the call to the desired office, and means for transmitting the remaining digits to the desired office without translation.

37. In a semi-automatic telephone system, means including an operator's key set for registering all the digits in a called number, means for translating the digits which have to do with the office selection into a suitable office code, impulse transmitting mechanism operated in accordance with said code, a series of automatic switches controlled by said mechanism to trunk the call to the desired office, means for then operating said mechanism to transmit series of impulses in

accordance with the untranslated digits, and a series of switches in the desired office responsive to said series of impulses to complete the connection to the called line.

5 38. In a multi-office telephone system in which all the telephone numbers have the same number of digits, means including an operator's key set for registering all the digits in a called number, means for translating those digits in the number which have to do with the office selection into a code, the number of digits in the code being variable and depending on the office in which the called station is located, impulse transmitting mechanism controlled in accordance with the code digits and the untranslated digits, and automatic switches controlled by the impulses transmitted by said sending mechanism to connect the calling and called 20 lines.

39. In a semi-automatic telephone system, an operator's position, a register sender, step-by-step switches controlled thereby, an operator's key set in said position, a translating switch included in said register sender, means to position said translating switch in accordance with the operated keys of said key set, and means for controlling said register sender to transmit a number of sets of impulses 25 to said step-by-step switches in accordance with the setting of said translating switch.

40. In a semi-automatic telephone system, an operator's position, a register sender, step-by-step switches controlled thereby, an operator's key set in said position, a translating switch included in said register sender, the keys of said key set operated in accordance with the number of digits in the office designation of the called line, means to position 30 said translating switch in accordance with the operated keys of said key set, and means for causing said register sender to transmit a different number of series of impulses to said step-by-step switches in accordance with 45 the setting of said translating switch.

41. In a semi-automatic telephone system, an operator's position, a register sender, step-by-step switches controlled thereby, an operator's key set in said position, a translating switch included in said register sender, the keys of said key set operated in accordance with the number of digits in the office designation of the called line, means to position 50 said translating switch in accordance with the operated keys of said key set, and means for causing said register sender to transmit a greater number of series of impulses to said

step-by-step switches in accordance with the setting of said translating switch.

42. In a semi-automatic telephone system, 60 an operator's position, a register sender, step-by-step switches controlled thereby, an operator's key set in said position, a translating switch included in said register sender, the keys of said key set operated in accordance 65 with the number of digits in the office designation of the called line, means to position said translating switch in accordance with the operated keys of said key set, and means for causing said register sender to transmit 70 a less number of series of impulses to said step-by-step switches in accordance with the setting of said translating switch.

43. In a semi-automatic telephone system, 75 an operator's position, a register sender, step-by-step switches controlled thereby, an operator's key set in said position, a translating switch included in said register sender, the keys of said key set operated in accordance 80 with the number of digits in the office designation of the called line, means to position said translating switch in accordance with the operated keys of said key set, and means for causing said register sender to transmit 85 a greater or a less number of series of impulses to said step-by-step switches in accordance with the setting of said translating switch.

44. In a semi-automatic telephone system, 90 a register sender, step-by-step switches controlled thereby, a free hunting translating switch included in said register sender, an operator's key set, means including operated 95 keys of said key set for positioning said translating switch in accordance with said operated keys, and means for controlling said register sender to generate and transmit a number of sets of impulses to said step-by-step switches in accordance with the setting 100 of said translating switch.

45. In a semi-automatic telephone system, 105 a register sender, step-by-step switches controlled thereby, a free hunting translating switch included in said register sender, an operator's key set, means including operated 110 keys of said key set for positioning said translating switch in accordance with said operated keys, and a counting device for cooperating with said translating switch to transmit a number of sets of impulses to said step-by-step switches in accordance with the setting of said translating switch.

In testimony whereof I affix my signature.
CHARLES GILLINGS.
